UNITED STATES PATENT OFFICE.

CHARLES STUBENBORD, OF NEW YORK, N. Y.

DESIGN FOR A STOVE.

SPECIFICATION forming part of Design No. 28,519, dated April 26, 1898.

Application filed March 10, 1898. Serial No. 673,404. Term of patent 7 years.

To all whom it may concern:

Be it known that I, CHARLES STUBENBORD, a citizen of the United States, residing at New York, in the county of New York and State of New York, have invented and produced a new and original Design for Stoves, of which the following is a specification, reference being had to the accompanying drawings, which form a part thereof, and in which—

- o Figure 1 is a front elevation of a stove showing my new design, and Fig. 2 is a sectional view taken on the line $x-x$ of Fig. 1.
- o As shown in the drawings, the leading or material feature of my design consists in a semicircular body forming a flat rear face or back and a curved or segmental front and comprising a flat top a and a flat base a' , respectively having straight rear edges a^2 and curved or segmental front edges a^3 , said top and base being connected by intermediate cylindrical portions. The top a and base a' are horizontally arranged, and the intermediate connecting cylindrical portions extend vertically between these parts. Said latter portions comprise a centrally-arranged main cylindrical part b , two outer cylindrical tu-

bular parts $c c$, respectively at opposite sides, and two inner cylindrical tubular parts $d d$, which two parts $d d$ are arranged at opposite sides of the longitudinal part b and extend upwardly from the base a' and have a right-angled top end d' , which extends inwardly to the part b . The top a is provided with an ornamental urn e , projecting upwardly from its top surface, while the base a' is provided with downwardly-extending angular projections f , and said base has a horizontal or flat flange g projecting laterally from its curved or segmental edge at the bottom.

Having fully described my invention, what I claim as new, and desire to secure by Letters Patent, is—

The design for a stove, substantially as herein shown and described.

In testimony that I claim the foregoing as my invention I have signed my name, in presence of the subscribing witnesses, this 8th day of March, 1898.

CHARLES STUBENBORD.
